UNITED STATES PATENT OFFICE.

WALTER H. SHEEHAN, OF STEUBENVILLE, OHIO.

COMBINED HEADLIGHT AND DIRECTION INDICATOR.

1,422,629.

Specification of Letters Patent. Patented July 11, 1922.

Application filed September 1, 1921. Serial No. 497,469.

To all whom it may concern:

Be it known that I, WALTER H. SHEEHAN, a citizen of the United States of America, and resident of Steubenville, county of Jefferson, and State of Ohio, have invented 5 certain new and useful Improvements in Combined Headlights and Direction Indicators, of which the following is a specification.

10 This invention relates broadly to headlights for motor vehicles, and it has for its primary object to provide a headlight embodying a peculiarly shaped reflector and means for indicating in both day and night 15 traffic the direction of travel.

A further object is to provide a reflector for headlights by which the light is reflected in such manner that much of the blinding glare resulting from the use of 20 ordinary parabolic reflectors is eliminated.

With these and other objects in view, the invention resides in the features of construction and arrangement of parts which will hereinafter be fully described, reference being had to the accompanying drawings, in 25 which—

Figure 1 is a front elevation of the reflector;

Figure 2 is a vertical section of a headlight embodying the invention;

Figure 3 is a similar section of a modified form of reflector and a lens therefor; and—

Figure 4 is a front elevation of the lens shown in Fig. 3.

35 Referring to said drawings, 1 indicates a lamp casing which may be of any ordinary or preferred form. Fitted within said casing in the usual manner is a sheet-metal reflector of which the lower and central portions, indicated by the numeral 2, possess the usual parabolic curvature, while the upper portion is shaped to form a horizontal forwardly-extending wall 3 located a short 40 distance above the axial center of the reflector; and extending vertically upward from the horizontal wall 3 and located slightly rearward of the position occupied by the usual glass lens 4 is a panel-like shield 5 which preferably forms an integral 45 part of the reflector.

The interior surface of the parabolically curved wall 2, as also the under surface of the horizontal wall 3, is polished or silvered for reflecting upon the roadway light 50 from a lamp 6 located as ordinarily in the axial center of the headlight. Obviously

the said horizontal wall 3 intercepts rays of light which would otherwise be directed outward in a forwardly and upwardly inclined direction, and reflects such rays in a 60 downwardly and forwardly inclined direction upon the roadway.

Provided in the flat vertical shield 5 which occupies the upper front portion of the headlight are cut out characters or indicia 65 12, such as the letters of the words "Right" or "Left," through which light may freely pass outward from a lamp 7 located behind said shield in the recess 8 formed by the offsetting of the reflector. The companion 70 headlights have the indicia thereof differing so that one or the other may be employed, as occasion may require, to indicate in traffic the direction of travel contemplated. For instance, the shield 5 of one 75 headlight may bear the word "Right" and the other the word "Left."

Suitably mounted upon one of the faces of the shield 5 in covering relation to the cut-out letters or other indicia is a strip or 80 sheet 9 of a transparent or translucent material, as isinglass or celluloid, through which the light from the lamp 6 may pass for illuminating such indicia, rendering the latter clearly visible to persons in front of 85 the vehicle. Said strip or sheet 9 is of a color corresponding with that of the outer face of the shield 5, which is preferably painted or enameled in green color, so that the indicia of the shield will not be visible 90 in daylight driving.

In night driving, the lamp 7 is switched on only when it is desired to indicate, in traffic, a change in the direction of travel, and the main lamp 6 is simultaneously 95 switched off in order that clear vision of the illuminated indicia may not thereby be obstructed.

In the modification illustrated in Figs. 3 and 4, an opening 10 approximating in size 100 the entire area of the upright wall 5^a is provided in the latter, and disposed in front thereof is a forwardly dished portion or shield 11 formed in a glass lens 4^a. Formed on said portion 11 in the manufacture of 105 the lens are raised letters or other suitable indicia 12^a. The said shield portion 11 is painted or otherwise coated to render it opaque, or substantially so, whereas the letters or indicia 12 are transparent so that 110 they are readily transmissive of light. As is obvious, signaling or indicating the direc-

tion of travel may be accomplished by this modified structure in a manner practically identical to that of the first hereinbefore described structure.

5 What is claimed is—

- A combined head light and direction indicator comprising a lamp casing, a reflector disposed within said casing, a lamp located within said reflector, said reflector having a substantially horizontal upper wall extending to the front of said casing, said wall being located slightly above the axial plane of said casing and being adapted to intercept and reflect downward substantially all of the upwardly directed rays from said lamp, a lamp disposed within said casing

above said wall, said reflector having formed integral therewith an upright wall forming a non-transparent shield located in front of the last mentioned lamp, said shield having openings cut therein in the form of direction indicia, and a covering of transparent material for said openings, said shield and said covering being of corresponding color. 20 25

In testimony whereof, I affix my signature in presence of two subscribing witnesses.

WALTER H. SHEEHAN.
